UNITED STATES PATENT OFFICE.

CHARLES B. ANDREWS, OF LEBANON, PENNSYLVANIA, ASSIGNOR TO THE
DIAMOND MATCH COMPANY, OF CHICAGO, ILLINOIS.

MATCH-BOX-SHUCK MACHINE.

SPECIFICATION forming part of Letters Patent No. 680,012, dated August 6, 1901.

Application filed August 11, 1900. Serial No. 26,616. (No model.)

To all whom it may concern:

Be it known that I, CHARLES B. ANDREWS, a citizen of the United States, residing at Lebanon, in the county of Lebanon, and in the State of Pennsylvania, have invented certain new and useful Improvements in Match-Box-Shuck Machines; and I do hereby declare that the following is a full, clear, and exact description thereof, reference being had to the accompanying drawings, in which—

Figure 1 is a plan view of a machine embodying my invention. Fig. 2 is a side elevation thereof. Fig. 3 is an end view of one of the strip-folding devices. Fig. 4 is a side elevation of another folding device. Fig. 5 is a plan view of the cutting, gluing, and sanding mechanisms; and Fig. 6 is a longitudinal sectional view of the mechanism shown in Fig. 5.

Letters of like name and kind refer to like parts in each of the figures.

The object of my invention has been to provide a machine for making shucks for match and other boxes which shall comprise improved devices for gluing, scoring, folding, and printing a strip of material, for cutting off the strip into shuck lengths and for sanding such lengths or any of such improved devices; and to such end it consists in the match-box-shuck machine hereinafter specified.

In carrying my invention into practice I provide a framework A, consisting of a bed a, supported by end legs a' and a' and intermediate legs a² and a². A driving-shaft B runs in bearings on cross-bars supported by the intermediate legs a² and a². A shaft C is similarly supported and is driven by means of a pinion b of the shaft B, which meshes with a gear-wheel c on the shaft C. A roll of paper, cardboard, strawboard, or other suitable material is supported on arms a³ and a³, extending horizontally from the rear legs a' and a', the roll having a rod which extends through an axial hole therein and the ends of such rod being supported in notches in the arms a³ and a³. At the rear end of the bed is a trough D for containing glue and having a glue-applying roll d', supported in bearings on a frame d², that is adapted to slide on the upper edges of the trough, such frame

having pins d³ and d³ attached to its sides, to which pins are connected springs d⁴ and d⁴, whose opposite ends are attached to pins d⁵ and d⁵ on the sides of the glue-trough. A small roll d⁶ is mounted under the bed a near its rear end, and a large roll E is mounted on top of such bed to the rear of the roll d⁶. The strip of material F passes forward of and over the roll d⁶, from which it extends rearward and around the roll E. The glue-applying roll d' extends into the glue and by means of the springs d⁴ and d⁴ is drawn against the strip as it passes over the roll E, such roll being positioned to engage the strip near its edge and being thus made to partake of the motion of the strip and to carry the glue up and apply it thereto, the strip being drawn forward by rolls at the forward end of the bed a, such rolls being hereinafter described.

In front of the roll E is a pair of brackets G and G, in the lower portion of which is mounted a plain roll g, above which is a scorer-roll g', the latter having bearing in blocks g² and g², which are mounted in ways in the brackets G and G, such blocks being pressed toward the roll g by screws g³ and g³, threaded in the brackets. The scorer-roll has four circular knives g⁴ and g⁴ mounted on its circumference, the knives being for the purpose of scoring the strip F where it is to be bent to form the corners of the shuck. The roll g has on its shaft a sprocket-wheel g⁵, which is connected by a sprocket-chain g⁶ with a sprocket-wheel g⁷ on the shaft C. A small roll H is mounted on the bed a in front of the roll g, and the strip F is supported thereon as it passes forward over the bed. From the scoring mechanism the strip passes to the front-folding device I, which device consists of a base i, from which rise two arms i' and i', which are inclined to each other and which are connected at the top by a bar i², having an arm i³ depending therefrom. To one of the arms i' a gage i⁴ is secured by a screw i⁵ passing through a slot therein, such gage having an arm i⁶, which extends at right angles to the arm, the lower edge of such arm being adapted to engage and guide one edge of the strip F. A second gage i⁷ is similarly secured to the other arm i', and such

second gage has an arm i^8 extending cross-wise of such arm i' and having a shoulder i^9 formed thereon, the under side of the arm i^8 engaging and guiding an edge of the strip F 5 and the shoulder i^9 serving to keep such edge of the strip against the arm i' . To the arm i^8 of the bar i^2 is secured a folding-blade i^{10} , such blade having a slotted shank i^{11} , which is secured by a screw to the arm i^8 . The 10 slots through which pass the screws which secure the gages and folding-blade to their supports enable these parts to be adjusted for various widths of strips and various positions of the scores in such strips. From the 15 folding device I the strip F passes between vertical plates K and K', which press together the portions of the strip which are on opposite sides of the score that was engaged by the folding-blade. The plate K is bolted to 20 the bed a by means of a flange on such plate, and the plate K' is secured to the plate K by means of screws passing through slots in the plate K' and threaded into holes in the plate K. The plate K' is shorter than the plate K, 25 so that it will not engage the glued edge of the strip F. The entrance of the space between the plates K and K' is flaring to facilitate the entrance of the paper. From the plates K and K' the strip F passes to a folding device 30 L, which consists of a plate secured to the bed a by a flange and having a plate l' and a flap-turner l^2 secured thereto. The plate l' is short and is secured to the plate l by screws passing through slots in said plate l' , so that 35 such plate can be adjusted vertically to enable it to engage the strip at and below the level of the flap when doubled over. The flap-turner l^2 is secured to the plate l by screws which pass through slots in the latter plate and 40 are threaded into the former plate. The flap-turner has on its under side a warped surface which engages the flap of the strip F and turns it over, so that its glued surface is pressed against the opposite portion of the strip. 45 From the folding device L the strip passes between two vertical rollers M and M', the latter being geared together and being mounted on vertical shafts m and m' , respectively, which are journaled below in the bed a and 50 above in a plate m^2 , that is supported on pillars m^3 and m^4 , rising from the bed a . The shaft m is extended below the bed and provided with a bevel-gear m^4 , which engages a bevel-gear c' on the shaft C. The rollers 55 M and M' serve to press the flap of the strip F into firm contact with the opposite edge of the strip. From the rolls M and M' the strip passes to a printing device N, consisting of an upper platen-roll n and a lower impression-roll, the rolls being geared together and the upper roll having inking-rolls n^2 and n^3 . 60

In front of the printing device is a bridge-piece O, which consists of a bar whose ends are bolted to the bed and from which ends 65 rise inclined portions that support a horizontal central portion. Two guides o and o' are adjustably bolted to the bridge-piece and

serve to keep the strip F centrally over the table. An apron P is secured to the bridge-piece and extends horizontally rearward 70 therefrom, its rear end portion being inclined downward and secured to the bed a . The strip after leaving the rolls M and M' is by means of the apron and bridge-piece given a quarter-turn, so that it lies horizontally across 75 the bed at the bridge-piece.

In front of the printing device N is a pair of brackets Q and Q', which are bolted to the bed and connected at the top by a shaft q . Two pairs of rolls q^1 and q^2 and q^3 and q^4 are 80 journaled in the brackets Q and Q', the bearing-boxes of the upper one of each of the pairs of rolls being mounted in vertical guides and being forced down by screws threaded in the brackets. The shafts of the second pair 85 of rolls q^3 and q^4 are extended beyond one of the brackets and provided with intermeshing gear-wheels q^5 and q^6 . The shaft of the lower roll also has a sprocket-gear q^7 , which is connected with a sprocket-gear q^8 on the shaft C 90 by a sprocket-chain q^9 . The gear q^6 also meshes with a gear q^{10} on the shaft q , which in turn meshes with a gear q^{11} on the shaft of the roll q^2 , and the latter gear meshes with a gear q^{12} on the shaft of the roll q^1 . The shaft 95 of the roll q^3 has a sprocket-gear which is connected by a sprocket-chain with a similar gear on the shaft of the upper printing-roll, and the printing mechanism is thus driven. The rolls q^1 and q^2 constitute the feeding-rolls, 100 and they travel at a speed somewhat greater than that of the pressing-rolls M and M', so that the strip is kept under tension between such pairs of rolls. The roll q^4 has a series of knives q^{13} and q^{14} radially secured in its periphery, such knives serving to cut against the roll q^3 and sever the strip F into shuck lengths. A bridge-piece R, similar to the bridge-piece 105 O and having similar guides r and r' , is bolted to the bed in front of the brackets Q and Q'. A pair of small feed-rolls S and S' is journaled in the brackets Q and Q just in front of the rolls q^3 and q^4 , the upper of which feed-rolls has a belt-pulley s on its shaft, over which pulley and a pulley s' on the shaft of 110 the roll q^1 runs a belt s^2 . From the small feed-rolls S and S' to the front end of the bed a extends a table T, whose front end is supported by a pair of legs t and t' , which are secured to the bed. Guides t and t' for the edges of the 115 shucks are secured to the table, and the shucks are prevented from rising or buckling by an overhanging guide t^2 , which is supported by cross-pieces extending from one of the guides t' . Beneath the table T is a glue-pan U, in 120 which dips a glue-applying roll u , whose upper edge extends to the upper surface of the table T through a slot. The shucks in passing over the table are thus glued along one side. A spring u' is fastened to the table and 125 presses the shucks against the glue-wheel. Beyond the glue-pan a cylindrical sand-receptacle V is secured to the table, and a paddle-wheel v is mounted to turn in such receptacle 130.

cle. An opening v' is formed in the table above the sand-receptacle, so that the paddle-wheel can throw the sand against the glued side of the shucks. The sand-receptacle is provided with a supply-opening v^2 at one side of the table. The glue-applying wheel has on one end of its shaft a sprocket-wheel, which is connected by a sprocket-chain with a similar wheel on the shaft of the roll q^3 . The opposite end of the shaft of the glue-applying roll also carries a sprocket-wheel, which is connected by a sprocket-chain with a similar wheel on the paddle-wheel shaft.

In the operation of my machine the strip F is drawn from the roll of material and is threaded over the roll d^6 and around the roll E , at which point the glue-applying roll d' applies glue to the edge of the strip which is to form the flap. The strip then passes under the scoring-roll, where the four scores f , f' , f^2 , and f^3 , that are to form the corners of the boxes, are made. The score f is nearest the glued edge, and the other scores occur in succession toward the opposite edge of the strip. From the scoring-roll the strip passes through the folding device I, its edges being guided by the gages i^4 and i^7 , so that the folding-blade i^{10} engages one of the middle scores in order that the flap of the strip when the latter is folded on such score shall extend beyond the opposite edge of the strip. After leaving the folding device I the strip passes between the plates K and K' , where the two portions of the strip on opposite sides of the score, acted upon by the folding-blade, are folded closely against each other, the glue on the flap not being disturbed, owing to the fact that the plate K' does not extend to the level of the glue. The warped surface of the folding device I turns over the glued flap and presses it against and secures it to the outer surface of the opposite portion of the strip. The folded and glued strip is now pressed perfectly flat by the pressing-rolls M and M' , after leaving which it is given a quarter-turn on its axis and passes through the printing device N , the apron P and the bridge-piece O , with its guides o and o' , serving to direct the strip horizontally and centrally into the printing device. From the printing device the strip passes over the bridge-piece R , being engaged by its guides r and r' , and is drawn forward by the feeding-rolls q' and q^2 , the latter traveling at a slightly-greater speed than the pressing-rolls, so that the strip shall be kept under tension between these pairs of rolls to prevent the glued parts of the flap from separating. After passing the feeding-rolls the strip is severed by the cutting-roll into shuck lengths, the latter being caught by the small feed-rolls S and S' between the guides t' and t' on the table T . Here the shucks are pressed against the glue-applying roll u by the spring u' and receive the glue by which the sand is to be secured to the shuck. The shucks then pass over the sand-receptacle, and sand is thrown

through the opening v' by the paddle-wheel and comes in contact with the glued portion of the shuck. The shuck then passes off the table T and is completed and ready to be opened merely by a lateral pressure.

Having thus described my invention, what I claim is—

1. In a machine for making box-shucks, a folding device for acting on a scored strip, such device consisting of a blade which acts only on a score of the strip, parts for turning the outer surfaces of the strip, and a gage for an edge of the strip, such gage having a shoulder which bears against the inner surface of the strip, substantially as and for the purpose described. 80
2. In a machine for making box-shucks, the combination of means for scoring a strip, means for gluing the strip near one edge thereof, a folding-blade which acts only on a score of the strip, parts for turning the outer surfaces of the strip, a gage for the glued edge of the strip, and a gage for the opposite edge of the strip, such latter gage having a shoulder which bears against the inner surface of the strip, substantially as and for the purpose described. 85
3. In a machine for making box-shucks, the combination with scoring devices, of a folding device consisting of a triangular frame, gages for the edges of the strip, such gages being on sides of the frame, and a folding-blade on the top of the frame and extending toward the angle of the frame, substantially 90 as and for the purpose described. 95
4. In a machine for making box-shucks, the combination with scoring devices, of a folding device consisting of a triangular frame, gages for the edges of the strip, such gages being adjustably secured on the sides of the frame, and a folding-blade adjustably secured on the top of the frame and extending toward the angle of the frame, substantially 100 as and for the purpose described. 110
5. In a machine for making match-box shucks, the shuck-sanding devices, comprising a table, a glue-pan beneath the table, a glue-wheel running in said pan and extending into an opening in said table, a leaf-spring extending over said opening and adapted to press the shucks against the glue-wheel, a sand-receptacle below the table, a wheel for throwing sand up through an opening in said table against the glued shuck, a pair of guides on said table for the shuck, and an overhanging guide supported between the said pair of guides, substantially as and for the purpose 115 described. 120

In testimony that I claim the foregoing I have hereunto set my hand this 14th day of June, 1900.

CHARLES B. ANDREWS.
